(57) **CLAIM**

The ornamental design for an illuminated loudspeaker, as shown and described.

DESCRIPTION

FIG. 1 is a front view of an illuminated loudspeaker, showing the new design; and,

FIG. 2 is a front view of another embodiment of the illuminated loudspeaker, showing the new design.

The evenly spaced broken lines illustrate portions of the design that form no part of the claimed design. The dash-dot broken lines represent the boundaries of the claimed design and form no part of the claimed design. The brighter arc-shaped areas represent illuminated portions of the loudspeaker face.
